UNITED STATES PATENT OFFICE.

WILLIS MANSFIELD, OF NEW HAVEN, CONNECTICUT.

HOUSE FOR SWITCH-TENDERS.

Specification of Letters Patent No. 11,431, dated August 1, 1854.

To all whom it may concern:

Be it known that I, WILLIS MANSFIELD, of the city of New Haven, county of New Haven, and State of Connecticut, have invented a new and Improved Switch-House, and that the following specification, taken in connection with the drawings, is a full, exact, and sufficient description thereof.

In the drawings, Figure 1 is an elevation 10 of one form of my improved switch-house, showing the switch etc. Fig. 2 is a vertical section through the same. Fig. 3 is a horizontal section on the line A B of Fig. 1, showing the house and switch in the position 15 which the various parts assume when the switch is open or placed in such position that cars must enter the turn out or siding. Fig. 4 is also a horizontal section showing the same parts in the position 20 which they assume when the switch is shut and in proper place for passing cars in either direction safely along the main track. Fig. 5 is a vertical section through a switch house of another form, with the switch, etc., 25 in the same position as in Fig. 4, and Fig. 6 is a horizontal section through the same house exhibiting by means of red lines, etc., the switch in three different positions.

In the running of rail roads there arise 30 many accidents, and there is perhaps no one cause that they may be so often fairly attributed to as a wrong set switch. Ingenious men have consequently devised many plans for obviating the danger arising 35 from such causes, and the whole class of self acting switches have been produced as the result of their labors. My mind has however, after long consideration and experience been led to pursue an entirely dif- 40 ferent track and I have become convinced that complete safety would be secured if it were only possible to prevent the switchman from leaving his post after he had opened a switch and until such time as the 45 switch should again be closed after the train had passed onto the siding. As the switch-tender is often employed on other duties than that of merely moving the switch it is not well in my opinion to dis- 50 pense with him altogether, as is the case in self acting switches, all that is necessary for safety being to oblige him to shut the switch prior to leaving his post.

The object of my invention therefore is 55 absolutely to prevent the switchman from

leaving his post so long as the switch remains open. After several attempts to secure this object in a practical manner it occurred that it could be attained by so constructing the door of his house that it would move in unison with the switch being open when the switch was shut and shut when the switch was open. I then placed the gate or apparatus which moved the switch within the switch-house and located the 60 switch-bolt or latch in the same inclosure, so that it was impossible to unlatch and move the switch without entering the house. If the switch be shut the house door must be open, and when the switch-tender desires 65 to open the switch he must enter the house in order to unlatch and operate the gate. As he performs the latter duty, he of necessity from the connection before mentioned 70 closes his door or the shutter to the aperture through which he entered his house and is confined therein until the gate is again operated to shut the switch. As the switch shuts the door opens and when the former is fully shut the latter is open to 75 such an extent as will permit the tender to leave his house to perform police or other duty in his immediate neighborhood until the time arrives for switching-off the next 80 train.

The nature of my invention therefore consists in connecting the door or doors of a switch house or their equivalents with the switch proper or some mechanism moving therewith in such manner that when the former is shut the latter shall be open and vice versa, when the switch and latch or 85 their equivalents are so arranged that the switch tender must enter his house to operate the switch proper substantially in the 90 manner hereinafter described.

Now I have devised many plans for carrying out the principles of my invention in a practical manner, and will proceed fully to describe one of them and also a method of embodying my invention practically under a slightly modified form. In the first place there is constructed a polygonal or cylindrical house (a a a) located properly near the switch, and erected upon a suitable bearing in said house is a vertical shaft (b). To the upper end of this shaft I secure a shutter (c c) with any convenient number of openings therein (d d). To the lower end of said shaft I secure a crank (e) and to a 100 105 110

wrist upon the same (f) I attach a connecting rod (g), which takes hold of the switch at (h). Around the shaft there is fastened a cylinder (i) with proper notches and guards thereon and to the shaft itself above the general plane of the top of the cylinder is attached a handle (k), which is in the present instance worked out into a spring (l), so that said handle may be moved vertically and act both as a lever and a latch. When the switch is shut or in proper position for the passing of trains along the main track, as shown in Fig. 4, the portions of the shutter or doors proper (c s) are opposite the solid portions of the house while the apertures (a o) in the house are opposite the openings (d d) in the shutter, the latch and lever is in the center notch (m) and the switch tender can enter and leave his house at pleasure; but when it becomes necessary to open the switch he must first enter the house and unlatch and then commence turning the lever; as he turns he opens the switch and causes the solid parts of the shutter to cover the openings into the house, so that when the switch is fully open all the shutters are covering all the apertures of the house and the switch tender is confined therein. He may now through a small window watch the train, and when all the cars are switched off he can again unlatch and shift his lever. As it is turned the shutters revolve, and when the switch is fully shut all portions of the apparatus assume the positions as exhibited in Fig. 4. If the switch be a double one, as shown in the drawings, and it be required to open it in the opposite direction to that shown in Fig. 3, the same movements of parts, but in a reverse direction, are effected, and when the switch is open the tender is shut in the house.

My arrangement of shutters as above described and as connected with the switch constitutes likewise a very convenient and easily observable signal which indicates to the engineer of an approaching train the position of the switch, whether open or shut. To produce this effect in the best manner it will be well to paint the outside of the house and the outside of the shutter in colors which are strong contrasts to each other, and the color which is painted upon the outside of the house should be a light one. When the switch is shut both colors will be seen in perpendicular alternate stripes, and when the switch is open one color only with intervals of shade or shadow will be visible. At night a lamp giving a bright light may be hung up within the house, and the appearance of parallel lines of light will indicate that the switch is shut, while the absence of light will show that the switch is open.

Now it is obvious any kind of switch gate and latch might be employed as a substitute for those herein described so long as they

are arranged in such manner as to render it necessary to enter the house in order to operate them. The shutter moreover may be moved by a motion derived from any part of the switch or gate through a suitable mechanical connection, or the shutter may only partially encircle the house if the apertures therein be properly located, or it may be replaced by a door, either sliding or swinging, so long as such door by means of a proper connection moves in unison with the switch, opening as the switch is shut and closing as the switch is opened. In fact, when the gate and latch are so located that the switch tender must enter his house as a prerequisite to opening the switch, then any contrivance which by means of a proper connection with the switch bars him in when the switch is open and gives him free passage when the switch is shut will be the equivalent of the revolving shutter herein described. It is easy moreover to multiply such contrivances to an indefinite extent.

Any materials may be used in constructing the house and it may be made on any plan and any kind of switch, switch gate and latch may be employed in connection therewith, my invention depending not upon their plan or construction but upon the connection between the shutter or its equivalents and a switch in such manner that the motions of the former are dependent upon the movements of the latter, as herein described, when the operating mechanism is so located that it is necessary to enter the house in order to put it in motion.

In some instances it might be well so to connect a door with a switch that the latter did not actually open the former, but only secured it shut when the switch was open. Such an arrangement is exhibited in Figs. 5 and 6, where a chain or cord (n) is attached to a switch at (o) and passed down between two pulleys (p p) and thence to an arm (q) attached to a door (r). When the switch is shut the door may be opened at will either from the inside or the outside, but when the switch is open it draws the chain or cord over one or other of the sheaves and shuts the door if it be open or locks it fast if it was shut after the switchman had entered his house. Red lines in Fig. 6 indicate the position which the various parts of the apparatus assume when the switch is open.

Any kind of sliding or swinging door may be employed in place of that exhibited in the last two figures, and any appropriate moving point of the apparatus may be selected for the attachment of the chain. It is clear therefore that the unbarring or unfastening of the door by the shutting of the switch is the equivalent of positively opening it by a motion derived from the shutting of the switch, and many modifications which will act substantially in this manner may be

devised which will still come within the scope of my invention. When therefore in this specification I say acting in unison with the switch, or words to that effect, I mean 5 acting really in such manner or in manner to produce the same effect so far as the locking or barring in of the switch tender when his switch is open is concerned.

Having thus clearly described one method 10 of applying the principle of my invention and indicated some of the various modes in which it may likewise be carried out I would state that I claim neither switches, switch-houses, switch-gates or latches; nor 15 do I claim any kind of door or shutter or connecting rods or their equivalents as a means of actuating the same; but

What I do claim as of my own invention

and desire to secure by Letters Patent of the United States is—

The connection between the switch house 20 door or its equivalent, and the switch or the actuating mechanism thereof, when said mechanism is arranged substantially in the manner described, said connection being substantially in the manner and for the purposes herein set forth.

In witness whereof I have hereunto subscribed my name in the presence of two witnesses on this fourth day of March, A. D. 30 1854.

WILLIS MANSFIELD.
